WASTE BASKET

Monte L. Levin, New York, N.Y., assignor to Pearl-Wick Corporation, Long Island City, N.Y., a corporation of New York

Filed Aug. 28, 1969, Ser. No. 18,902

Term of patent 14 years

Int. Cl. D7—06

U.S. Cl. D49—30

FIG. 1.

FIG. 2.

FIG. 3.

FIG. 1 is a front or rear elevational view of a waste basket showing my new design;

FIG. 2 is a top view thereof; and

FIG. 3 is a left or right side view thereof.

The design is symmetrical and open at the top.

I claim:

The ornamental design for a waste basket, substantially as shown and described.
